UNITED STATES PATENT OFFICE.

GEORGE C. BAKER, OF DES MOINES, IOWA.

MECHANISM FOR PROPELLING VESSELS.

SPECIFICATION forming part of Letters Patent No. 358,425, dated March 1, 1887.

Application filed July 6, 1886. Serial No. 207,214. (No model.)

To all whom it may concern:

Be it known that I, GEORGE C. BAKER, a citizen of the United States, residing at Des Moines, in the county of Polk and State of Iowa, have invented new and useful Mechanism for Propelling Vessels, of which the following is a specification.

The object of my invention is to provide a mechanism for propelling and guiding aerial and marine vessels by means of a pair of screw-propellers attached on the opposite sides of the central portion of the vessel in such a manner that they can be readily adjusted and retained in position, as required, for directing the vessel's course vertically and laterally. This object I attain by the mechanism illustrated in the accompanying drawings, in which—

Figure 1 is a top view of a vessel with the mechanism attached; Fig. 2, a cross-section of the same, and Fig. 3 a detail view of the sleeve and its bearing.

Similar letters refer to similar parts throughout the several views.

25 The main shaft A, provided at its extreme outer ends with the bevel-gears b b and at its center with a crank, C, or any equivalent means of transmitting motion from the engine, rotates in the sleeves D D, which rest in boxes or bearings E E, attached in any secure manner to the sides of the vessel F. The sleeves D D are provided at their outer ends, which project outside of the vessel, with arms g g, standing at right angles with the body of the sleeve. From the arms g g two bearings, h h, extend outward, and are provided at their ends with boxes to carry the shafts m m. One end of each shaft m, which rests parallel with the sides of the vessel, is provided with a common screw-propeller, n, and the other end with a bevel-gear, o, which engage the bevel-gear b b at the extreme end of the main shaft A.

To the inner ends of the sleeves D D and inside of the vessel are attached levers p p, with racks r r, or any suitable form of hand or automatic mechanism, for adjusting and setting the sleeves D D and propellers n n in any desirable position to guide the vessel upward, downward, in a circular or in a reverse course. By 50 this form of mechanism it will be seen that by throwing the propellers in different angles relative to the keel of the vessel it may be

made to move upward or downward in air or water, and when attached to a marine structure the principle may be applied to the directing of submarine torpedo-boats, &c. 55

I further wish to emphasize as an important feature of my invention the central arrangement of the main shaft A with the propellers n n as a more perfect means of managing a 60 vessel.

I am aware that a propeller has been combined with the end of a vessel in such a manner that it could be raised and lowered in a circle about a center to advance a vessel in 65 water in one direction only; but my construction, arrangement, and combination of two propeller-wheels with the opposite sides of the central portion of a vessel and mechanism for adjusting and operating the wheels independently and also jointly at pleasure, for the purpose of raising or lowering the vessel, advancing it horizontally, reversing its motion, and steering it in any direction desired, is 70 novel and greatly advantageous. 75

I claim as my invention—

1. The combination of the main shaft A, provided at its ends with sleeves resting in bearings in the sides of the vessel, which sleeves are adapted to carry propellers operating in conjunction with the main shaft A, and provided with means of adjusting the same, substantially as specified, and for the purposes stated. 80

2. The main shaft A, provided with the sleeves D D, resting in bearings E E, which sleeves have arms g g extending from their outer ends at right angles, and projecting outward from which are the bearings h h, carrying the propeller-shafts m m, which operate in 90 conjunction with the main shaft A by means of the bevel-gears b b and o o, and the whole provided with means for adjusting the sleeves and propellers, substantially as set forth, and for the purposes stated. 95

3. A driving-shaft having bevel-gears on its ends, sleeves having arms extending at right angles from their outer ends, carrying propeller-wheels, and mechanism for rotating and adjusting the sleeves, arranged and combined with a vessel, to operate in the manner set forth, for the purposes stated. 100

4. A vessel having a driving-shaft extended horizontally and transversely through its cen-

tral portion, sleeves upon the ends of said shaft, arms extending at right angles from the outer ends of said sleeves, propeller-wheels in bearings extending at right angles from said arms, mechanism for rotating said sleeves, and mechanism for operating the propeller-wheels carried on the arms extending from

said sleeves, arranged and combined to operate in the manner set forth, for the purposes stated.

GEORGE C. BAKER.
